UNITED STATES PATENT OFFICE.

THOMAS S. CATLIN, OF GUION, INDIANA, ASSIGNOR OF ONE-HALF TO HARDY W. ROBBINS, OF GWINNEVILLE, INDIANA.

JAR-HOLDER.

1,217,565.

Specification of Letters Patent. Patented Feb. 27, 1917.

Application filed February 21, 1916. Serial No. 79,676.

To all whom it may concern:

Be it known that I, THOMAS S. CATLIN, a citizen of the United States, residing at Guion, in the county of Parke and State 5 of Indiana, have invented certain new and useful Improvements in Jar-Holders; and I do hereby declare the following to be a full, clear, and exact description of the invention, such as will enable others skilled 10 in the art to which it appertains to make and use the same.

This invention relates to improvements in gripping devices, and more particularly to such as are adapted for gripping jars and 15 like containers.

The primary object in view is the provision of means for gripping jars of different standard sizes by means also adapted to grip jars of slightly varying sizes from the 20 standard size.

With these and other detail objects in view, the invention comprises certain novel constructions, combinations, and arrangements of parts as will be hereinafter specified and claimed.

In the accompanying drawing:

Figure 1 is a plan view of a gripping device embodying the features of the invention, parts being broken away and seen 30 in section.

Fig. 2 is a side elevation thereof.

Figs. 3 and 4 are fragmentary perspective views of the free end portions of the strap sections.

Fig. 5 is a view in elevation of the inside 35 face of one of the strap sections and showing its connection with the operating lever.

Referring to the drawing by numerals, 1, 1 indicate the long arms of operating levers which are pivoted together at 2, and having their short arms 3, 3 extending beyond the pivot, and each provided at its outer extremity with an eye 4. Through each eye 4 is looped the respective end of what may be considered the clamping band which consists of two sections, being a section 5 and a section 6. Each section has its end portion looped through the respective eye 4 and looped back upon itself and formed into a tongue 7 which is extended through a slot 8 formed in the respective section of the clamping band. The tongue 7 in each instance is bent down against the inner face of the band. The material of each short arm 3 is stamped for forming

the eye 4 and the material thus stamped out is bent back upon a portion of the remaining material of the arm to form a somewhat transversely oval-shaped piece 9. As the loop is of substantially the same 60 shape, it will be free to move through the eye for a certain distance, but the oval shape of the piece 9 will tend to prevent the respective section from falling so far away from the other section as not to be 65 susceptible of easy manipulation with respect thereto.

The section 5 is formed with outstanding ears or tabs 10, 10 at its edges, each being formed with an elongated slot 11, between 70 its outer portion and the band section 5, opening toward the other band section 6. There are as many pairs of the ears or tabs 10 provided as there are standard sizes of the types of jars to be handled. For example, there are three sizes of the well known Mason jars, being pints, quarts and half gallons. A set of the ears or tabs 10 is provided for each of these standard 75 sizes.

The section 6 is of a width to fit snugly between the tabs 10 throughout its length except for the extreme free end portion, which is provided with shoulders 12, 12, outstanding in a direction for entering the 80 notches 11, and engaging the outstanding portions of the tabs 10. Beyond the shoulder portion 12, the end portion of section 6 is curved outward to form a finger engaging lip 13. From the shoulder 12 outward to a point near the beginning of the tab 13, the material of the section 6 is widened and formed with longitudinal slots 14, 14, each of the slots being of a length sufficient for enabling introduction of one 95 of the tabs 10, the space between the slots 14 being equal to the width of the main portion of section 6, so that a pair of the tabs 10 may be introduced through the pair of slots 14.

In operation, when standard jars are being handled, to apply the clamping band to the largest size jar, the section 6 is placed over the section 5 with the shoulders 12 in position engaging the notches 11. This can be done by first swinging the sections apart a distance sufficient to allow the sections to be passed about the opposite sides of the body of the jar and then brought to the interlocked position; or the sections may be 100 105 110

interlocked and then slid endwise over the jar. When positioned about the jar and interlocked, the sections may be caused to grip the jar tightly merely by gripping the handles or operating levers 1. This gripping of the jars may be for the purpose of applying a lid or for removing a lid or otherwise as occasion may require. The releasing of the jar merely requires the releasing 10 of the handles 1 and either the sliding of the clamping band endwise off the jar or the detaching of the sections by the withdrawal of the shoulders 12 from within notches 11 and the swinging of the sections 15 apart. The application of the clamp to an intermediate size jar will be the same as described except that the shoulders 12 will engage the notches 11 of the intermediate section, and the same operation is employed 20 for applying the clamp to the smallest size jar except that the shoulders 12 engage the last of the set of tabs 10.

There has been placed on the market recently certain jars which are not of the heretofore standard size, and vary therefrom only slightly, each of the several sizes being slightly larger than the standard size. To enable the improved clamp to be applied to these extra size jars, the slots 14 are employed, and the operation is identically the same as that above described except that the tabs 10 in each instance are passed through the slots 14 instead of being caused to engage the shoulders 12.

35 What I claim is:

1. The combination, with hand operating levers, of band sections adapted to form a clamping band and each having one end portion engaging the operating levers, one 40 of said sections being formed with a tab and the other with a coöperating shoulder

to permit interlocking of the sections while being clamped about a jar, the section having a shoulder being also formed with a slot 45 adapted to accommodate the tab for locking the sections together with the tab spaced from the shoulder.

2. The combination, with hand operating levers, of band sections adapted to form a clamping band and each having one end 50 portion engaging the operating levers, one of said sections being formed with a pair of tabs, and the other with a coöperating pair of shoulders to permit interlocking of the sections while being clamped about a 55 jar, the shouldered section being also formed with a pair of slots spaced from the shoulders for accommodating the pair of tabs and enabling locking of the sections together with the tabs spaced from the shoul- 60 ders.

3. The combination, with a pair of operating levers, of band sections adapted to form a clamping band, and each having one end portion engaging the operating levers, 65 one of said sections being formed with outstanding tabs spaced apart lengthwise of the section, and the other section being formed with a shoulder adapted to co-operate with any one of said tabs for connecting the sections together to permit clamping thereof about a jar, the shoulder section being also formed with a tab receiving slot spaced from the shoulder and adapted to engage any of said tabs for locking 70 the sections together.

In testimony whereof I affix my signature in presence of two witnesses.

THOMAS S. CATLIN.
